UNITED STATES PATENT OFFICE.

MAX W. VOIGTMAN, OF ST. LOUIS, MISSOURI.

MACHINE FOR AFFIXING MATERIAL TO AND EMBELLISHING BOOK COVERS.

1,424,269.

Specification of Letters Patent. Patented Aug. 1, 1922.

Application filed September 23, 1920. Serial No. 412,300.

To all whom it may concern:

Be it known that I, MAX W. VOIGTMAN, a citizen of the United States of America, residing at St. Louis, in the State of Missouri, have invented a new and useful Machine for Affixing Material to and Embellishing Book Covers, of which the following is a specification.

This invention has for its prime object the provision of a simple, compact, durable and inexpensive machine comprising means for rapidly performing the operation of turning a narrow margin of linen, canvas, leather or other suitable material over upon the inner surface of the boards forming the cover of a book, and for scoring or otherwise embellishing the outer surface of the cover.

Referring to the accompanying drawing, Figure 1 is a front elevation of the complete machine; Figure 2 a side elevation thereof taken along line 2—2 of Figure 1; Figure 3 a detail sectional view taken along line 3—3 of Figure 1; Figure 4 a top plan view depicting the inner surface of a book-cover with the material-affixing devices in engagement therewith; Figure 5 a fragmentary detail, on enlarged scale, of the elements shown in Figure 4; Figure 6 a side view of the frame element hereinafter described; Figure 7 a top plan view of the bed upon which the book-cover is disposed; and Figure 8 a perspective of one of the devices employed for pressing the material at the corners of the cover when covers with rounded corners are being made.

The machine comprises a pair of standards 1 provided with guide-ways 2 for the reception of guide-blocks 3—4 formed integral with plate 5 which is also provided with tapered extensions 6 secured to rods 7—7^a by threaded bolts 8. Disposed beneath said plate is the bed 9 upon which the book-cover 10 is laid after the linen, canvas, leather or other material has been affixed to its outer surface, and by reference to Figure 3 it will be noted that said bed rests within the upturned flange 11 of plate 12 and may be adjusted with respect to the upper edge of said flange by insertion or withdrawal of an intermediate plate 13. The upper edge of flange 11 is preferably mortised or slotted at intervals for the provision of a plurality of segments 14 which fit within the similarly mortised lower edge of pressing-bars 15 as

shown (in dotted outline) in Figure 5, said segments being hingedly connected by the projection therethrough of a pin 16.

When books having rounded corners are to be covered, the plate 12 then employed will have a corresponding form and a plurality of pressing devices such as shown in Figure 8 will supplant flange 11 at the corners of said plate. Said devices consist of a bracket 17 (having the same height and thickness as said flange) secured to said plate by screws 18 and slotted at 19 for the reception of a wedge-shaped member 20 hingedly supported between bracket-arms 17^a by pin 21 which, when the parts are assembled, has the same location as hinge 16.

Surrounding flange 11 is a frame 23 having a plurality of pins 24 depending from its under surface which project through a stationary plate 25 affixed to standards 1 and contact with a vertically movable plate 26 having guide-blocks 27 extending within guide-ways 2, it being noted by reference to Figures 1 and 3 that the hinge line 16 of pressing-bars 15 is considerably above said frame when the latter is at rest so that said bars may be forced upward and outward, with members 20, as hereinafter described.

Secured to the under surface of bed 9 by screws 28 is a block 29 which extends through apertures of corresponding size in plates 12 and 13 and terminates directly above cam 30 affixed to shaft 31. Said shaft is supported by adjustable bearings 32 and connected with rods 7—7^a by cranks 33, rod 7 being also connected by crank 34 with stub-shaft 31^a which is rotated by hand-wheel 35 and supported by adjustable bearing 36. Shaft 31 is further supported adjacent to cam 30 by standards 37 having a convex base 38 resting upon concave blocks 39 and surmounted by half-bearings 40, and it will be appreciated that a shim or shims 41 may be employed to compensate for the wear of said bearings and that, by reason of the described formation of elements 38—39, said standards may be positioned beneath said shaft after the machine has been assembled.

If it is desired to score or impress the outer surface of the cover, a shallow groove is cut in bed 9 and a steel rule 42 is laid therein as shown in Figures 5 and 7 or a die may be sunk in the bed should other ornamentation be required.

The operation of the machine is as follows. Cloth, linen, leather or other material having been affixed with glue to one side of the boards which are to form the cover of the book and said boards thus hingedly connected, the cover is then placed upon bed 9 with the uncovered side of said boards uppermost and with a narrow margin of the material brought over the edges of the boards. This margin is denoted in Figures 4 and 5 by numeral 42 and may be observed upon inspection of any book having covered boards. The object now being to evenly and quickly secure said margin to the inner surface of the boards, shaft 31 is rotated through the agency of wheel 35 and pins 43 secured to said shaft are thus brought against plate 26 whose upward movement against pins 24 serves to lift frame 23 upon which pressing-bars 15 and pressing members 20 are resting as shown in Figures 1 and 3. Said bars and members are thus forced inward with reference to flange 11 of plate 12 and press said margin of the covering material firmly against said boards as shown in Figures 4 and 5, this position being maintained until bed 9 is raised by engagement of cam 30 with the lower extremity of block 29, and as the bed with the cover thereon emerges from said flange said bars and members are lifted and returned to the position shown in Figure 3 and the entire cover is then pressed by plate 5 which

has been moved downward by rotation of cranks 33-34.

Having thus fully described the invention, what I claim as new and desire to secure by Letters Patent is:—

1. A machine of the character described comprising a bed adapted to support a book-cover, a plate beneath said bed having an upturned flange surrounding said bed, members hingedly connected with said flange, a frame enclosing said flange, means for lifting said frame against said members to position the latter against said cover, and mechanism for raising said bed subsequent to the operation of said means to position said members against said frame.

2. A machine of the character described comprising a bed adapted to support a book-cover, a plate beneath said bed having an upturned flange surrounding said bed, members hingedly connected with said flange, a frame enclosing said flange, means for lifting said frame against said members to position the latter against said cover, mechanism for raising said bed subsequent to the operation of said means to position said members against said frame, and devices for pressing the entire cover after removal therefrom of said members.

MAX W. VOIGTMAN.
